COMPOSITION AND METHOD FOR
DESUCKERING TOBACCO

Jean Bradley Harrison, Niagara Falls, N.Y., assignor to
E. I. du Pont de Nemours and Company, Wilmington,
Del., a corporation of Delaware
No Drawing. Filed Mar. 15, 1965, Ser. No. 440,015
11 Claims. (Cl. 71—2.6)

This application is a continuation-in-part of my co-pending application Serial No. 236,149, filed November 7, 1962; which in turn is a continuation-in-part of my application Serial No. 139,595, filed September 21, 1961, both now abandoned.

This invention relates to methods for the chemical treatment of tobacco plants. More specifically, it relates to the treatment of tobacco plants in the topping stage with compositions of esters of carbanilic acids for the purpose of controlling axillary bud growth.

Sucker growth, a term given for axillary bud growth, is an age-old problem in the tobacco industry. It dates back to the grower's realization that good quality smoking tobacco leaf contains a high amount of sugar and that axillary buds on tobacco plants use this sugar for growth. The farmer's problem, therefore, has been to eliminate sucker growth economically and without any harmful side effects to the desirable tobacco leaf. Heretofore, chemical substances have been known to decrease sucker growth in tobacco plants, but with undesirable side effects to the tobacco leaves.

The compounds used in this invention overcome this problem when sprayed on tobacco plants in the topping stage by preventing or markedly inhibiting the growth of suckers and decreasing the loss of leaf sugar without adversely affecting the leaves of the plant. The result is an increase in the amount of high quality smoking tobacco leaf.

My invention is the treating of tobacco plants in a crucial point of their development, namely in the topping stage, with a compound having the following general formula:

wherein

X, Y and Z are the same or different and are each chlorine, bromine, fluorine, alkyl of 1 through 4 carbon atoms and alkoxy of 1 through 4 carbon atoms;

m, n and t are each 0 or 1;

R' is vinyl, methylvinyl, chloromethylvinyl, hydroxymethylvinyl, ethynyl, methylethynyl, hydroxymethylethynyl, chloromethylethynyl, 1-hydroxyalkyl, 1-chloroalkyl and 1-bromoalkyl where the alkyl group is 1 through 4 carbon atoms and CH_2Q ;

Q is hydrogen, chlorine, bromine, hydroxy, alkyl, monochloroalkyl, monobromoalkyl, hydroxyalkyl, and methoxyalkyl where the alkyl is 1 through 4 carbon atoms, alkoxy of 1 through 4 carbon atoms, alkoxyalkyl, alkenyl, chloralkenyl, bromoalkenyl and alkynyl of 2 through 4 carbon atoms, hydroxyalkenyl, hydroxyalkynyl, chloroalkynyl and bromoalkynyl of 3 through 4 carbon atoms and alkoxyalkenyl and alkoxyalkynyl of 3 through 6 carbon atoms with the limitation that R and R' cannot both be an ethylenic or acetylenic unsaturation at the same time, and at least one of m, n and t must be 1.

R is hydrogen, chlorine, alkyl, monochloroalkyl,

2

monobromoalkyl, hydroxyalkyl, and methoxyalkyl where the alkyl is 1 through 4 carbon atoms, alkoxy of 1 through 4 carbon atoms, alkoxyalkyl, alkenyl, chloroalkenyl, bromoalkenyl and alkynyl of 2 through 4 carbon atoms, hydroxyalkenyl, hydroxyalkynyl, chloroalkynyl and bromoalkynyl of 3 through 4 carbon atoms and alkoxyalkenyl and alkoxyalkynyl of 3 through 6 carbon atoms with the limitation that R and R' cannot both be an ethylenic or acetylenic unsaturation at the same time, and at least one of m, n and t must be 1.

Although all the compounds within this application are preferred, particularly preferred compounds because of their outstanding activity in reducing sucker growth at low rates are those of the formula:

wherein

X and Y are chloro or methyl;

m is 0 or 1;

R is hydrogen, methyl, ethyl, methoxymethyl, chloromethyl, 1-chloroethyl, alkenyl of C_1-C_3 or alkynyl of C_1-C_3 ; and

Q is hydrogen or chlorine.

It is customary in the tobacco raising industry to break out the main stem by hand when 75 to 90% of the tobacco plants are in flower. This operation is called topping.

Generally, compounds used in this invention are applied to tobacco plants during the topping stage. Specifically, the compounds used in this invention are applied during the period of seven days before to four days after topping in an amount of active compound sufficient to inhibit sucker growth. Conveniently, they are applied by spraying in emulsions or powder suspensions in water. Ordinarily, application at the rate of 0.125 to 6 and preferably 2 to 5 pounds active ingredient per acre will be used.

By treating tobacco plants in the above manner particularly outstanding results are achieved. Sucker growth on tobacco plants is inhibited without injury to the remainder of the tobacco plant. The net result is a larger yield of good quality smoking tobacco.

Compositions of this invention are prepared in a manner similar to the compositions described in Luckenbaugh U.S. Patent 2,935,393 issued May 3, 1960. The Luckenbaugh patent is herein incorporated by reference. The compositions, therefore, will contain the active agent combined with a surfactant and either an emulsifiable oil to provide a liquid media or an inert solid diluent to provide a powder form of the composition.

Additional surfactant can be added to the above formulation to increase the ratio of surfactant:active agent up to as high as 20:1 by weight. Particularly preferred compositions contain 0.25:1 to 5:1, surfactant:active agent by weight.

A particularly preferred composition because of its persistency on the plant and ease of dispersion is one containing 2 to 15% by weight of diethanolamine, triethanolamine, di-isopropanolamine or tri-isopropanolamine, 6 to 35% by weight of dodecylbenzenesulfonic acid, 30 to 60% by weight of isophorone and 10 to 30% by weight of m-chlorocarbanilic acid, isopropyl ester or m-chlorocarbanilic acid, ester with 1,3-dichloro-2-propanol.

The compounds of this invention are prepared by methods well known in the art. Two convenient routes are illustrated below.

Route I, the reaction of an aromatic amine (A) with an alkyl haloformate (B) in the presence of an acid acceptor to form a carbanilate is well known to the art. The acid acceptor may be a second equivalent of the aromatic amine (Hentschel, Ber. 18, 978), pyridine (Chattaway, J. Chem. Soc., 117, 710), tertiary aliphatic organic bases such as triethylamine, as well as inorganic bases such as sodium bicarbonate, sodium carbonate (Schmidt, Ph. Ch., 58, 516) or sodium hydroxide (Brit. 780,713/57). The reaction can be run in the absence of solvent, in indifferent organic solvents (benzene, xylene, ether, petroleum, etc.), or in water (Brit. 780,713/57; Can. 522,141/56; W. J. Hickinbottom, "Reactions of Organic Compounds," Longmans, Green and Co., 3rd ed., 1957, p. 403). Reaction temperatures may be from -20° to 100° with a preferred range of 0° to 30° . During the course of the reaction the acid acceptor forms an acid acceptor hydrohalide.

If the reaction is run in a solvent such as xylene, the acid acceptor hydrohalide generally precipitates and may be removed by filtration. Evaporation of the filtrate yields essentially pure product.

This product may be either a liquid or a solid at room temperature. If a solid it may generally be recrystallized. If a liquid it may generally be distilled under reduced pressure.

The haloformates (B) are prepared by well-known literature procedures (for example, the reaction of phosgene plus an alcohol). Where Q equals Cl, it is con-

venient to prepare the haloformate from phosgene plus an epoxide.

See U.S. 2,820,810 (C.A., 52:11, 897d) and Jones, J. Chem. Soc., 1957, 2735.

10 Iso structures generally predominate and normal structures

are not obtained. The yield, however of

in the method of Jones was markedly reduced by the pronounced tendency of the formed chloroformate to react with a second equivalent of epoxide with the formation of the symmetrical carbonate. U.S. 2,820,810

25 describes the reverse addition whereby the epoxide is added to liquid phosgene containing a catalytic amount of hydrogen halide. Under these conditions the reverse addition results in high yields of chloroformate. We have found that by the reverse addition of an epoxide to phosgene containing pyridine as a catalyst high yields of chloroformate are obtained.

30 Route II, the reaction of an aromatic isocyanate (C) with an alcohol (D) to form a carbanilate is well known to the art [Saunders, Chem. Rev., 43, 203 (1948); Gumpert, J. Prakt. Chem., 31, 119 (1885); Gumpert, J. Prakt. Chem., 32, 278 (1885); Knoevenagel, Ann., 297, 148 (1897)]. The reaction may be run in the absence of solvents or in the presence of indifferent solvents (benzene, xylene, petroleum ether, ethyl ether, etc.) and at temperatures ranging from 0 to 100° . These reactions may be non-catalyzed [Baker, J. Chem. Soc., 1947, 713; Dyer, J. Am. Chem. Soc., 71, 4106 (1949)] or catalyzed by any of a number of basic catalysts, for example tertiary amines [Saunders, Chem. Rev., 43, 203 (1948)], triethylamine [Burrus, J. Am. Chem. Soc., 80, 5948 (1950)], diethyl aniline (Baker, *locus cit.*), or pyridine (Baker, *locus cit.*).

35 40 45 50 55 This invention will be better understood by referring to the following illustrative examples. All percentages are by weight unless otherwise stated.

Example 1

m-Chlorocarbanilic acid, ester with 1,3-dichloropropanol-2 is formulated according to the following recipe:

	Percent
m-Chlorocarbanilic acid, ester with 1,3-dichloropropanol-2	35
Commercial mixture of ethylenediamine salt of dodecylbenzene sulfonic acid and polyoxethylene sorbitan monolaurate (Atlox 4600)	35
Isophorone	30

60 65 The above homogeneous solution is prepared by simple mixing of the mutually soluble components.

This formulation is applied at the rate of two pounds of active ingredient in 40 to 100 gallons water per acre to flue-cured and air-cured tobacco before or after topping. Excellent control of suckers, also called axillary buds, is obtained over a period of 40 days. Rates as low as 0.5 pound per acre give effective control for 14 to 28 days. Control of suckers results in increased yield of tobacco leaves with better smoking quality.

5

Example 2

Another method of formulating and using m-chlorocarbanilic acid, ester with 1,3-dichloropropanol-2 is as follows:

	Percent
m-Chlorocarbanilic acid, ester with 1,3-dichloropropanol-2	20
Isooctylphenylpolyethoxyethanol ("Triton" X-100)	20
Sodium lignin sulfonate	4
Hydrated attapulgite clay	2.5
Water	53.5

All of the above components except the isoctylphenylpolyethoxyethanol are mixed together and sand milled until the active component has a particle size of 10 microns or less. After milling, the isoctylphenylpolyethoxyethanol is added with mild stirring.

The above formulation is applied in 60 gallons of water at the rate of two pounds of active ingredient per acre to air-cured (light) tobacco such as burley, before or after topping. Excellent sucker control is noted during the harvest season without noticeable injury to the tobacco plants.

Example 3

The compound, 2,5-dichlorocarbanilic acid, ester with 1,3-dichloro-2-propanol, may be formulated and used as the following recipe:

	Percent
2,5-dichlorocarbanilic acid, ester with 1,3-dichloro-2-propanol	30
Polyoxyethylene sorbitan monolaurate ("Tween" 20)	30
Cyclohexanone	40

The above components are mutually soluble when mixed together.

This formulation is used at the rate of two pounds of active ingredient per acre for the control of tobacco suckers as described in Example 1.

Example 4

2,5-dichlorocarbanilic acid, ester with 1,3-dichloro-2-propanol is also used on tobacco when formulated in the following manner:

	Percent
2,5-dichlorocarbanilic acid, ester with 1,3-dichloro-2-propanol-2	30
Sodium lauryl sulfate	30
Attapulgite clay	40

A wettable powder is prepared from the above components by blending and micropulverizing.

When used at the rate of two to four pounds per acre of active ingredient in 60 gallons of water at topping time, excellent sucker control for an extended period is obtained on flue-cured tobacco.

Example 5

When m-chlorocarbanilic acid, ester with 1-chloro-2-propanol is blended with the formulating ingredients shown, it is useful for controlling tobacco suckers as described.

	Percent
m-Chlorocarbanilic acid, ester with 1-chloro-2-propanol	35
Isooctylphenylpolyethoxyethanol ("Triton" X-100)	35
Isophorone	30

When mixed together, these components form a clear solution which may readily be emulsified in water.

This formulation is used according to the technique of Example 1 to control sucker growth of topped tobacco plants.

6

Example 6

When o-chlorocarbanilic acid, ester with 1,3-dichloro-2-propanol is formulated according to the following recipe, it may be used as described below.

	Percent
o-Chlorocarbanilic acid, ester with 1,3-dichloro-2-propanol	20
Trimethylnonyl ether of polyethylene glycol	20
Cyclohexanone	60

These components are mutually soluble to form a clear solution which emulsifies readily in water.

The above formulation is applied in 60 gallons of water at the rate of two pounds of active ingredient per acre to air-cured tobacco before or after topping. Excellent sucker control is noted during the harvest season without apparent injury to the tobacco plants.

Example 7

20 The formulation and use of m-chlorocarbanilic acid, ester with 2-chloroethanol is as follows:

	Percent
m - chlorocarbanilic acid, ester with 2 - chloroethanol	35
Commercial mixture of the ethylenediamine salt of dodecylbenzenesulfonic acid and polyoxyethylene sorbitan monolaurate (Atlox 4600)	20
Isophorone	45

When mixed, the above components yield a clear solution which readily emulsifies in water.

When used at the rate of 3 pounds per gallon of active ingredient in 60 gallons of water at topping time, excellent sucker control for an extended period is obtained on flue-cured tobacco.

Example 8

The formulation and use of m-chlorocarbanilic acid, ester with isopropanol for control of tobacco suckers is illustrated below.

	Percent
m-Chlorocarbanilic acid, ester with propanol-2	35
Polyethoxynonylphenol	20

An emulsifiable solution is prepared by mixing together 45 the above components.

This formulation is applied at the rate of 1 to 2 pounds of active ingredient per acre to control suckers on tobacco plants according to the methods of Example 1.

Example 9

50 m-Chlorocarbanilic acid, sec-butyl ester is formulated and used in the following manner:

	Percent
m-Chlorocarbanilic acid, sec-butyl ester	35
Sodium dodecylbenzene sulfonate	20

Synthetic fine silica

Blending and micropulverizing the above components gives a wettable powder which disperses readily in water.

This formulation is used at the rate of 2 pounds of 60 active ingredient per acre as described in Example 4.

Example 10

2,5-dichlorocarbanilic acid, isopropyl ester is formulated and used as follows:

	Percent
2,5-dichlorocarbanilic acid, isopropyl ester	30
Polyoxyethylated tall oil	15

2-heptanone

A homogeneous, emulsifiable solution is prepared by 70 mixing together the above components.

The above formulation is used at the rate of 2 pounds of active ingredient per acre in 60 gallons of water for the control of tobacco suckers. Application is made when the tobacco is topped. Good sucker control is obtained.

Example 11

The compound, m-chlorocarbanilic acid, ester with 1-chloro-2-propanol is used and formulated as follows:

	Percent
m-Chlorocarbanilic acid, ester with 1-chloro-2-propanol	40
Diethyl sodium sulfosuccinate condensed 85-15 with sodium benzoate ("Aerosol" OTB)	15
Attapulgite clay	45

The above wettable powder is prepared by blending and micropulverizing the components to a particle size below 50 microns.

This formulation is used for control of suckers on tobacco grown for cigar production. An application of 15 two pounds of active ingredient per acre applied at or near the topping stage gives satisfactory control of suckers during the harvest period.

Example 12

m-Chlorocarbanilic acid, ester with isopropanol is formulated as follows:

	Percent
m-Chlorocarbanilic acid, ester with isopropanol	20
Isooctylphenylpolyethoxyethanol ("Triton" X-100)	20
Sodium lignin sulfonate	4
Hydrated attapulgite clay	2.5
Water	53.5

The above ingredients except the isoctylphenylpolyethoxyethanol are mixed together and sand milled until the active component has a particle size of 10 microns or less. After milling, the isoctylphenylpolyethoxyethanol is added with mild stirring.

This formulation is used for the control of tobacco sucker according to the procedure of Example 2.

Example 13

2,5-dichlorocarbanilic acid, sec-butyl ester is formulated as follows:

	Percent
2,5-dichlorocarbanilic acid, sec-butyl ester	30
Polyoxyethylene sorbitan monolaurate ("Tween" 20)	30
Cyclohexanone	40

The above components are mutually soluble when mixed together.

This formulation is used at the rate of two pounds of active ingredient per acre for the control of tobacco suckers according to the procedures of Example 14.

Example 14

m-Chlorocarbanilic acid, isopropyl ester is formulated and used in the following manner:

	Percent
m-Chlorocarbanilic acid, isopropyl ester	35
Commercial mixture of ethylenediamine salt of dodecylbenzene sulfonic acid and polyoxyethylene sorbitan monolaurate (Atlox 4600)	35
Isophorone	30

The above homogeneous solution is prepared by simple mixing of the mutually soluble components.

This formulation is applied at the rate of two pounds of active ingredient per acre in 40 to 100 gallons of water per acre to tobacco before or after topping. Excellent control of suckers (axillary buds) is obtained over a period of 40 days. Control of the suckers results in increased yield of tobacco leaves.

Example 15

	Percent
m-Chlorocarbanilic acid, ester with 1,3-dichloro-2-propanol	25
Triethanolamine	10
Dodecylbenzenesulfonic acid	20
Isophorone	45

The m-chlorocarbanilic acid, ester with 1,3-dichloro-2-propanol and triethanolamine are dissolved in the solvent isophorone. The dodecylbenzenesulfonic acid is then added slowly with cooling.

Since the acid strength of different lots of dodecylbenzenesulfonic acid may vary, it is necessary prior to formulation to determine by titration the amount of triethanolamine required to neutralize the dodecylbenzenesulfonic acid being used so as to obtain a mixture which is neither excessively acidic nor excessively alkaline. If desired, xylene, toluene or other alkylated benzenes can be substituted for part of the isophorone.

The above formulation is applied at the rate of 1 to 2 pounds per acre of active ingredient to the leaves of tobacco plants such as flue-cured and burley types. These plants are topped when approximately 90% are in flower. The application is made with the active emulsified in 40-60 gallons of water. The water acts as a carrier and as a means to facilitate contact of the active material with most of the leaves on each treated plant. This treatment gives long-lasting sucker control on tobacco plants topped just prior or immediately after treatment. An increase in the yield of tobacco leaf is noted.

Example 16

	Percent
m-Chlorocarbanilic acid, ester with 1-methoxy-2-propanol	20.0
Triisopropanolamine	6.2
Dodecylbenzenesulfonic acid	13.8
Isophorone	60.0

The m-chlorocarbanilic acid, ester with 1-methoxy-2-propanol and the triisopropanolamine are dissolved in the isophorone. The dodecylbenzenesulfonic acid is slowly added to this mixture with cooling. If desired, tolene, xylene, or other alkylated benzenes can be substituted for part of the isophorone.

This material is applied as a foliar spray to tobacco plants topped when 90% of the plants are in flower. By applying 1.5 pounds per acre of active ingredient in 100 gallons of water, the spray contacts most of the leaves on each treated plant. This treatment inhibits the growth of tobacco suckers and increases the yield of smoking leaf.

Example 17

	Percent
m-Chlorocarbanilic acid, ester with 3-chloro-2-butanol	30.0
Dodecylbenzenesulfonic acid	24.1
Diisopropanolamine	11.8
Isophorone	34.1

The m-chlorocarbanilic acid, ester with 3-chloro-2-butanol and the diisopropanolamine are dissolved in the isophorone. The dodecylbenzenesulfonic acid is slowly added to the mixture while cooling.

This compound is applied as a foliar spray at the rate of 2 to 3 pounds of active ingredient per acre in 50 gallons of water during the time that approximately 90% of the tobacco plants are in flower. Care is used to secure adequate coverage of tobacco foliage. The tobacco plants are topped the following day. The growth of tobacco suckers is prevented by this treatment. The yield of tobacco is increased.

Example 18

	Percent
m-Chlorocarbanilic acid, ester with isopropanol	36.0
Diethanolamine	2.5
Dodecylbenzenesulfonic acid	6.5
Xylene	55.0

The m-chlorocarbanilic acid, ester with isopropanol and the diethanolamine are dissolved in the xylene. The dodecylbenzenesulfonic acid is added slowly to the mixture. A cooling bath is employed to remove the heat of neutralization. Triethanolamine at 3.3% can replace

the diethanolamine in this formulation. The percent of xylene used is adjusted to correct for the increase in amine content.

The above composition is applied as a foliar spray to properly topped tobacco at the rate of two pounds per acre of active ingredient in 40 gallons of water. Treatment with this chemical effectively inhibits the growth of tobacco suckers and results in increased yields of tobacco.

Example 19

	Percent
m-Chlorocarbanilic acid, ester with 3-butyn-2-ol	15
Triethanolamine	15
Dodecylbenzenesulfonic acid	30
Isophorone	40

The m-chlorocarbanilic acid, ester with 3-butyn-2-ol and the triethanolamine are dissolved in the isophorone. The dodecylbenzenesulfonic acid is slowly added to the mixture. A cooling bath is used to remove the heat of neutralization.

This formulation is applied as a foliar spray at the rate of 2 to 3 pounds per acre of active ingredient in an emulsion of 50 to 75 gallons of water. Before spraying, the tobacco plants are topped when approximately 90% of the plants are in flower. This treatment prevents the growth of the axillary buds on tobacco plants and results in an increased yield of tobacco leaf.

Example 20

	Percent
2,5-dichlorocarbanilic acid, ester with 3-butyn-1-ol	15
Dodecylbenzenesulfonic acid, sodium salt	75
Synthetic fine silica	10

The active ingredient, 2,5-dichlorocarbanilic acid, ester with 3-butyn-1-ol is ground in a hammer mill until its particle size is substantially less than 30 microns. Following the grinding, all of the ingredients are thoroughly blended in a ribbon blender.

This wettable powder formulation is applied at the rate of 4 pounds per acre of active ingredient in 50 to 75 gallons of water. When this suspension is applied as a foliar spray to topped tobacco, the growth of suckers is prevented. This inhibition of sucker growth results in increased yields of smoking leaf.

Example 21

	Percent
2,5-dichlorocarbanilic acid, ester with 4-ethoxy-4-penten-1-ol	50.0
Dodecylbenzenesulfonic acid, potassium salt	12.5
Partially desulfonated sodium lignin sulfonates	0.5
Kaolinic clay	37.0

All of the above ingredients are thoroughly blended and ground in a hammer mill until the particle size is essentially less than 30 microns.

A slurry is made by mixing 8 pounds of this wettable powder with a small quantity of water. The slurry is then diluted to 75 gallons with water. The mixture is applied as a foliar spray on one acre of topped tobacco. Care is used to keep the powder suspended and to obtain good coverage of the foliage. This treatment gives good sucker control on topped tobacco.

Example 22

	Percent
m-Chlorocarbanilic acid, ester with 6-chloro-4-hepten-2-ol	40.0
Dodecylbenzenesulfonic acid, sodium salt	40.0
Partially desulfonated sodium lignin sulfonate	0.5
Kaolinic clay	19.5

All of the ingredients are thoroughly blended together and ground in a hammer mill or other grinding equipment until the particle size is essentially less than 30 microns.

Sixteen pounds of this material is suspended in 100 to 150 gallons of water and the suspension is sprayed on two acres of tobacco. The tobacco is topped immediately following application. This foliar treatment gives good inhibition of the growth of suckers.

Example 23

	Percent
m-Chlorocarbanilic acid, ester with 1,2-propanediol	25
Blend of polyalcoholcarboxylic acid ester and sulfonated oils	6
Isophorone	69

The m-chlorocarbanilic acid, ester with 1,2-propanediol and the emulsifier, blend of polyalcoholcarboxylic acid esters and sulfonated oils, are dissolved in the isophorone.

Four pounds of the active material formulated as indicated above are emulsified in 50 gallons of water. Five pounds of the triethanolamine salt of dodecylbenzenesulfonic acid are added to this mixture and dissolved by agitation. This mixture is applied as a foliar spray on an acre of topped tobacco. The growth of tobacco suckers is inhibited by the treatment.

Example 24

	Percent
2,5-dichlorocarbanilic acid, ester with 3-butyn-2-ol	20
Blend of alkylaryl sulfonates and nonylphenol polyoxylethylene condensation products	6
Xylene	34
Isophorone	40

The formulation is prepared by stirring all of the ingredients together until the solid is dissolved and the solution is homogeneous.

Four pounds of the triisopropanolamine salt of dodecylbenzenesulfonic acid are dissolved in a small quantity of water and the solution diluted to 50 gallons with water. Fifteen pounds of the emulsifiable formulation outlined above are added to the water solution and agitated. The resulting emulsion is sprayed as a foliar application on an acre of tobacco which is topped when 80-90% of the plants are in flower. This treatment effectively controls sucker growth of the tobacco plants.

Example 25

	Percent
m-Chlorocarbanilic acid, ester with 1-chloro-3-buten-2-ol	30
Blend of alkylaryl sulfonates and nonylphenol polyoxylethylene condensation products	8
Isophorone	62

The ingredients are stirred together until the solid is dissolved and the solution is uniform.

If desired, benzene, toluene or xylene can be substituted for part of the isophorone.

Five pounds of the diethanolamine, salt of dodecylbenzenesulfonic acid are dissolved in 50 to 75 gallons of water. Alternatively, a like amount by weight of the triethanolamide salt can be used. Eight pounds of the above formulation are emulsified in the water solution and the emulsion sprayed as a foliar treatment on an acre of topped tobacco. Good sucker control is obtained.

Example 26

	Percent
m-Chlorocarbanilic acid, ester with 1-chloro-3-buten-2-ol	25
Dodecylbenzenesulfonic acid	20
Triisopropanolamine	9
Isophorone	23
Xylene	23

The formulation is prepared by dissolving the m-chlorocarbanilic acid, ester with 1-chloro-3-buten-2-ol and the triisopropanolamine in the isophorone and xylene. The dodecylbenzenesulfonic acid is slowly added with cooling.

Three pounds of active ingredient in the above formulation are emulsified in 40 to 60 gallons of water and applied by foliar spray to topped tobacco. The treatment inhibits the growth of tobacco suckers during the harvest period.

Example 27

	Percent
m-Chlorocarbanilic acid, ester with isopropanol	25
Dodecylbenzenesulfonic acid	20
Triethanolamine	10
Xylene	45

The m-chlorocarbanilic acid ester with isopropanol, triethanolamine and xylene are thoroughly mixed and the dodecylbenzenesulfonic acid is added slowly. A cooling bath is used to remove the heat generated upon the introduction of the acid.

This formulation is applied as a foliar spray at the rate of two pounds of active ingredients per acre in 40 to 60 gallons of water to leaves of topped tobacco plants, such as flue-cured and burley types. Approximately 90% of the tobacco plants are usually in flower when the tobacco plants are topped. Excellent sucker control is obtained during the harvest period.

Example 28

	Percent
m-Chlorocarbanilic acid, ester with 1-chloro-2-propanol	30.0
Dodecylbenzenesulfonic acid	15.0
Triisopropanolamine	13.2
Isophorone	41.8

The m-chlorocarbanilic acid, ester with 1-chloro-2-propanol and the triisopropanolamine are dissolved in the isophorone. The dodecylbenzenesulfonic acid is added slowly with cooling.

Two to four pounds of active ingredient in the above formulation is emulsified in 50-75 gallons of water and sprayed on an acre of tobacco such as flue-cured, burley, or dark air cured types. The tobacco is topped within 36 hours after treatment. This treatment prevents the growth of tobacco suckers and increases the yield of tobacco leaf.

Example 29

	Percent
m-Chlorocarbanilic acid, ester with 1-hexyn-3-ol	25
Dodecylbenzenesulfonic acid	20
Diethanolamine	6
Toluene	20
Isophorone	29

The m-chlorocarbanilic acid, ester with 1-hexyn-3-ol and the diethanolamine are dissolved in the toluene and isophorone. The dodecylbenzenesulfonic acid is added slowly with cooling.

From 10 to 24 pounds of this formulation are added to 50 to 100 gallons of water and applied to an acre of topped tobacco, using care to obtain good coverage of the leaves. The treatment effectively inhibits the growth of suckers on the topped tobacco.

Examples 30-150

The following compounds are each substituted one at a time for the m-chlorocarbanilic acid, ester with 1,3-dichloro-2-propanol of Example 15 in like amount by weight and are formulated in like manner. Like results are achieved.

Ex.

30. m-Chlorocarbanilic acid, isopropyl ester
31. o-Chlorocarbanilic acid, isopropyl ester
32. 2,5-dichlorocarbanilic acid, sec-butyl ester
33. 2,3,5-trichlorocarbanilic acid, ethyl ester
34. m-Chlorocarbanilic acid, ester with 1-chloro-2-propanol
35. m-Methylcarbanilic acid, ester with 1,3-dichloro-2-propanol

36. 2,5-dichlorocarbanilic acid, ester with 1,3-dichloro-2-propanol
37. o-Chlorocarbanilic acid, ester with 1,3-dichloro-2-propanol
38. p-Chlorocarbanilic acid, amyl ester
39. m-Bromocarbanilic acid, isopropyl ester
40. m-Chlorocarbanilic acid, ester with 1-methoxy-2-hydroxy-propane
41. m-Fluorocarbanilic acid, isopropyl ester
42. m-Fluorocarbanilic acid, ester with 1,3-dichloro-2-propanol
43. 2,5-dichlorocarbanilic acid, methoxyethyl ester
44. m-Chlorocarbanilic acid, beta-chloroethyl ester
45. o-Chlorocarbanilic acid, ester with 1,3-dimethoxy-2-propanol
46. m-Chlorocarbanilic acid, ester with 1-bromo-2-propanol
47. m-Chlorocarbanilic acid, ester with 1,4-diisopropoxy-5-hexyn-2-ol
48. m-Methylcarbanilic acid, isopropyl ester
49. m-Butylcarbanilic acid, 2-chloroethyl ester
50. 2-methoxy-5-chlorocarbanilic acid, sec-amyl ester
51. 4-n-butoxy carbanilic acid, ester with 1,3-dichloro-2-propanol
52. 2,5-dichlorocarbanilic acid, ester with 1-methoxy-2-propanol
53. 2,3-dichloro-5-methylcarbanilic acid, isopropyl ester
54. 2-fluoro-5-methylcarbanilic acid, beta-chloroethyl ester
55. m-Chlorocarbanilic acid, butoxyethyl ester
56. m-Bromocarbanilic acid, ester with 1-chloro-3-methoxy-2-propanol
57. m-Chlorocarbanilic acid, ester with 2-chloroethanol
58. m-Chlorocarbanilic acid, ester with 1-bromo-3-chloro-2-propanol
59. o-Bromocarbanilic acid, ester with 1-methoxy-2-propanol
60. 2,3,6-trichlorocarbanilic acid, ester with 3-chloro-2-butanol
61. p-Chlorocarbanilic acid, ester with 1-chloro-3-methyl-2-butanol
62. 2-methyl-5-chlorocarbanilic acid, ester with sec-amyl alcohol
63. 2,3,6-trichlorocarbanilic acid, ester with 1,3-dichloro-2-propanol
64. 2-chloro-5-methylcarbanilic acid, ester with 1-chloro-2-propanol
65. 2-chloro-5-n-butylicarbanilic acid, ester with 1,3-dichloro-2-propanol
66. m-Chlorocarbanilic acid, ester with 1,3-dimethoxy-2-propanol
67. m-Bromocarbanilic acid, 2-chloro-ethyl ester
68. m-Fluorocarbanilic acid, ester with 2-(n-butoxy) ethanol
69. p-Chlorocarbanilic acid, ester with 1-ethoxy-2-propanol
70. o-Chlorocarbanilic acid, ester with 3-pentanol
71. m-Chlorocarbanilic acid, ester with 3-methyl-2-butanol
72. 2,5-dichlorocarbanilic acid, isopropyl ester
73. m-Chlorocarbanilic acid, sec-butyl ester
74. m-Chlorocarbanilic acid, monoester with ethylene glycol
75. m-Chlorocarbanilic acid, monoester with 1,2-propanediol
76. o-Chlorocarbanilic acid, ester with propargyl alcohol
77. m-Chlorocarbanilic acid, ester with allyl alcohol
78. 2,5-dichlorocarbanilic acid, ester with allyl alcohol
79. 2,5-dichlorocarbanilic acid, ester with 3-butyn-2-ol
80. m-Chlorocarbanilic acid, ester with 1-chloro-3-butene-2-ol
81. o-Chlorocarbanilic acid, ester with methallyl alcohol
82. 2,5-dichlorocarbanilic acid, ester with 3-butyn-1-ol
83. m-Chlorocarbanilic acid, ester with 4-pentyn-2-ol
84. o-Chlorocarbanilic acid, ester with 4-pentyn-2-ol

85. o-Chlorocarbanilic acid, ester with 1-pentyn-3-ol
 86. m-Chlorocarbanilic acid, ester with 1-hexyn-3-ol
 87. m-Chlorocarbanilic acid, monoester with 2-butyne-1,4-diol
 88. m-Chlorocarbanilic acid, ester with 4-chloro-2-butyne-1-ol
 89. 2,5-dichlorocarbanilic acid, monoester with 2-butene-1,4-diol
 90. m-Chlorocarbanilic acid, ester with 4-chloro-2-butene-1-ol
 91. o-Chlorocarbanilic acid, ester with 2-butyne-1-ol
 92. m-Chlorocarbanilic acid, ester with 2-chloro-1-propanol
 93. m-Chlorocarbanilic acid, monoester with 2,5-hexanediol
 94. 2,5-dichlorocarbanilic acid, ester with 3-methylene-2-pentanol
 95. o-Chlorocarbanilic acid, ester with 5-chloro-3-penten-2-ol
 96. m-Chlorocarbanilic acid, ester with 4-chloro-3-butene-2-ol
 97. m-Chlorocarbanilic acid, monoester with 3-hexene-2,5-diol
 98. 2,5-dichlorocarbanilic acid, ester with 1,4-dimethoxy-5-hexyn-2-ol
 99. 2,5-dichlorocarbanilic acid, ester with 4-ethoxy-3-penten-1-ol
 100. o-Chlorocarbanilic acid, ester with 1-bromo-3-hexyn-2-ol
 101. m-Chlorocarbanilic acid, ester with 5-chloro-3-pentyn-2-ol
 102. m-Chlorocarbanilic acid, ester with 5-bromo-3-hexyn-2-ol
 103. m-Chlorocarbanilic acid, 4-ester with 2-pentyn-1,4-ol
 104. m-Chlorocarbanilic acid, monoester with 3-hexen-2,5-diol
 105. m-Chlorocarbanilic acid, ester with 6-chloro-4-hepten-2-ol
 106. o-Chlorocarbanilic acid, ester with 1-chloroethanol
 107. m-Chlorocarbanilic acid, ester with 1-bromoethanol
 108. 2,5-dichlorocarbanilic acid, 1-ester with 1,2-pentanediol
 109. 2,5-dichlorocarbanilic acid, ester with 2-chloro-1-pentanol
 110. o-Chlorocarbanilic acid, ester with 2-bromo-1-propanol
 111. o-Chlorocarbanilic acid, ester with 2-bromo-1-pentanol
 112. m-Chlorocarbanilic acid, ester with 1-chloro-3-heptanol
 113. m-Chlorocarbanilic acid, ester with 6-chloro-1-hexanol
 114. 2,5-dichlorocarbanilic acid, ester with 5-chloro-2-hexanol
 115. o-Chlorocarbanilic acid, ester with 1,4-dibromo-2-butanol
 116. m-Chlorocarbanilic acid, 3-ester with 4-bromo-1,3-heptanediol
 117. m-Chlorocarbanilic acid, ester with 6-bromo-1-hexanol
 118. 2,5-dichlorocarbanilic acid, ester with 1-methoxy-2-chloroethanol
 119. m-Chlorocarbanilic acid, ester with 1-butoxy-2-chloroethanol
 120. o-Chlorocarbanilic acid, ester with 1-isopropoxy-2-propanol
 121. o-Chlorocarbanilic acid, monoester with 1,6-hexanediol
 122. m-Chlorocarbanilic acid, ester with 4-chloro-3-butene-2-ol
 123. 2,5-dichlorocarbanilic acid, ester with 3-bromo-3,5-hexadien-2-ol
 124. m-Chlorocarbanilic acid, 4-ester with 1-hexene-3,4-diol

125. 2,5-dichlorocarbanilic acid, ester with 3,5-hexadien-2-ol
 126. o-Chlorocarbanilic acid, ester with 5-bromo-3-pentyl-2-ol
 5 127. m-Chlorocarbanilic acid, ester with 4-methoxy-3-butene-2-ol
 128. m-Chlorocarbanilic acid, ester with 5-ethoxy-3-butene-2-ol
 129. m-Chlorocarbanilic acid, ester with 4-methoxy-3-butyn-2-ol
 10 130. m-Chlorocarbanilic acid, ester with 5-ethoxy-3-butene-2-ol
 131. m-Chlorocarbanilic acid, ester with 4-penten-2-ol
 132. o-Chlorocarbanilic acid, ester with 5-methyl-5-hexen-2-ol
 15 133. m-Chlorocarbanilic acid, ester with 3-methoxy-1-propanol
 134. m-Chlorocarbanilic acid, ester with 3-isopropoxy-1-propanol
 20 135. 2,5-dichlorocarbanilic acid, ester with 4-chloro-3-butene-1-ol
 136. 2,5-dichlorocarbanilic acid, ester with 6-chloro-4-heptyn-2-ol
 137. o-Chlorocarbanilic acid, ester with 4-bromo-3-butene-1-ol
 25 138. o-Chlorocarbanilic acid, ester with 6-bromo-4-hepten-2-ol
 139. m-Chlorocarbanilic acid, ester with 3-hexyn-1-ol
 140. m-Chlorocarbanilic acid, 2-ester with 5-hexene-2,4-diol
 30 141. m-Chlorocarbanilic acid, monoester with 3-hexen-1,6-diol
 142. m-Chlorocarbanilic acid, 1-ester with 3-pentyn-1,5-diol
 35 143. m-Chlorocarbanilic acid, monoester with 3-hexen-1,6-diol
 144. o-Chlorocarbanilic acid, ester with 5-chloro-3-pentyn-2-ol
 145. o-Chlorocarbanilic acid, ester with 5-bromo-3-pentyn-2-ol
 40 146. 2,5-dichlorocarbanilic acid, ester with 6-bromo-4-hepten-2-ol
 147. m-Chlorocarbanilic acid, ester with 5-methoxy-4-penten-2-ol
 45 148. m-Chlorocarbanilic acid, ester with 4-isopropoxy-3-penten-1-ol
 149. m-Chlorocarbanilic acid, ester with 5-methoxy-4-penten-2-ol
 The invention claimed is:
 50 1. The method comprising applying a foliar spray to tobacco plants while the plants are in the topping stage said spray comprising a desuckering amount of a compound of the formula:
- 55 - where
- 60 X, Y and Z are each selected from the group consisting of chlorine, bromine, fluorine, alkyl of 1 through 4 carbon atoms, and alkoxy of 1 through 4 carbon atoms; m, n and t are each selected from the group consisting of 0 and 1;
- 65 R₁ is selected from the group consisting of vinyl, methylvinyl, chloromethylvinyl, hydroxymethylvinyl, ethynyl, methylethynyl, hydroxymethylethynyl, chloromethylethynyl, 1-hydroxyalkyl, 1-chloroalkyl and 1-bromoalkyl where each alkyl group is 1 through 4 carbon atoms and CH₂Q;
- 70 Q is selected from the group consisting of hydrogen, chlorine, bromine, hydroxy, alkyl, monochloroalkyl, monobromoalkyl, hydroxyalkyl, where each alkyl is 1 through 4 carbon atoms, alkoxy of 1 through 4 carbon atoms, alkoxyalkyl, alkenyl, chloroalkenyl, bromoalkenyl
- 75

nyl, and alkynyl of 2 through 4 carbon atoms, hydroxy-alkenyl, hydroxyalkynyl, chloroalkynyl and bromoalkynyl of 3 through 4 carbon atoms and alkoxyalkenyl and alkoxy alkynyl of 3 through 6 carbon atoms; and R is selected from the group consisting of hydrogen, chlorine, bromine, alkyl, monochloroalkyl, monobromoalkyl, hydroxyalkyl, where each alkyl is 1 through 4 carbon atoms, alkoxy of 1 through 4 carbon atoms, alkoxyalkyl, alkenyl, chloroalkenyl, bromoalkenyl and alkynyl of 2 through 4 carbon atoms, hydroxyalkenyl, hydroxyalkynyl, chloroalkynyl and bromoalkynyl of 3 through 4 carbon atoms and alkoxyalkenyl and alkoxyalkynyl of 3 through 6 carbon atoms, with the limitation that R and R₁ cannot both be selected from the group consisting of ethylenic and acetylenic unsaturations at the same time, and with the further limitation that one of m, n and t must be 1.

2. The method comprising applying to tobacco plants during the period of seven days before to four days after topping a desuckering amount of a compound of the formula:

where

X, Y and Z are each selected from the group consisting of chlorine, bromine, fluorine, alkyl of 1 through 4 carbon atoms, and alkoxy of 1 through 4 carbon atoms; m, n and t are each selected from the group consisting of 0 and 1;

R₁ is selected from the group consisting of vinyl, methylvinyl, chloromethylvinyl, hydroxymethylvinyl, ethynyl, methylethyne, hydroxymethylethyne, chloromethylethyne, 1-hydroxyalkyl, 1-chloroalkyl and 1-bromoalkyl where each alkyl group is 1 through 4 carbon atoms and CH₂Q;

Q is selected from the group consisting of hydrogen, chlorine, bromine, hydroxy, alkyl, monochloroalkyl, monobromoalkyl, hydroxyalkyl where each alkyl is 1 through 4 carbon atoms, alkoxy of 1 through 4 carbon atoms, alkoxyalkyl, alkenyl, chloroalkenyl, bromoalkenyl, and alkynyl of 2 through 4 carbon atoms, hydroxyalkenyl, hydroxyalkynyl, chloroalkynyl and bromoalkynyl of 3 through 4 carbon atoms and alkoxyalkenyl and alkoxyalkynyl of 3 through 6 carbon atoms; and

R is selected from the group consisting of hydrogen, chlorine, bromine, alkyl, monochloroalkyl, monobromoalkyl, hydroxyalkyl, where each alkyl is 1 through 4 carbon atoms, alkoxy of 1 through 4 carbon atoms, alkoxyalkyl, alkenyl, chloroalkenyl, bromoalkenyl and

alkynyl of 2 through 4 carbon atoms, hydroxyalkenyl, hydroxyalkynyl, chloroalkynyl and bromoalkynyl of 3 through 4 carbon atoms and alkoxyalkenyl and alkoxyalkynyl of 3 through 6 carbon atoms, with the limitation that R and R₁ cannot both be selected from the group consisting of ethylenic and acetylenic unsaturations at the same time, and with the further limitation that one of m, n and t must be 1.

3. A composition especially useful for application to tobacco plants comprising 2 to 15% by weight of a compound selected from the group consisting of triethanolamine, di-ethanolamine, di-isopropanolamine and tri-isopropanolamine, 6 to 35% by weight of dodecylbenzenesulfonic acid, 30 to 60% by weight of isophorone and 10 to 30% by weight of a compound selected from the group consisting of m-chlorocarbanilic acid, isopropyl ester; and m-chlorocarbanilic acid, ester with 1,3-dichloro-2-propanol.

4. Method according to claim 1 wherein the compound applied is m-chlorocarbanilic acid, isopropyl ester.

5. Method according to claim 1 wherein the compound applied is m-chlorocarbanilic acid, ester with 1,3-dichloro-2-propanol.

6. Method according to claim 1 wherein the compound applied is m-chlorocarbanilic acid, ester with 1-methoxy-2-propanol.

7. Method according to claim 1 wherein the compound applied is m-chlorocarbanilic acid, ester with 2-methyl-3-butyn-2-ol.

8. Method according to claim 1 wherein the compound applied is 2,5-dichlorocarbanilic acid, ester with 3-butynol.

9. Method according to claim 1 wherein the compound applied is o-chlorocarbanilic acid, ester with 2-chloroethanol.

10. Method according to claim 1 wherein the compound applied is m-chlorocarbanilic acid, ester with 3-butyn-2-ol.

11. Method according to claim 1 wherein the compound applied is m-chlorocarbanilic acid, ester with 1-chloro-2-propanol.
